UNITED STATES PATENT OFFICE.

RICHARD W. GERTZ, OF BROOKLINE, MASSACHUSETTS.

AGRAFFE.

1,353,904.

Specification of Letters Patent. Patented Sept. 28, 1920.

Application filed December 20, 1918. Serial No. 267,570.

To all whom it may concern:

Be it known that I, RICHARD W. GERTZ, a citizen of the United States, residing at Brookline, county of Norfolk, State of Massachusetts, have invented an Improvement in Agraffes, of which the following description, in connection with the accompanying drawing, is a specification, like characters on the drawing representing like parts.

This invention relates to piano construction and particularly to the construction of the agraffe, and the object of the invention is to provide a novel agraffe which is simple in construction and easily manufactured and which will firmly retain its proper position when the piano is used.

In order to give an understanding of my invention I have illustrated in the drawings some selected embodiments thereof which will now be described, after which the novel features will be pointed out in the appended claims.

In the drawings Figure 1 is a sectional view of a portion of a grand piano having my invention applied thereto.

Fig. 2 is a fragmentary sectional view showing my invention applied to an upright piano.

Fig. 3 is an underside plan view of a portion of the piano frame, illustrated in Fig. 1, showing the relative arrangement of the different agraffes.

Fig. 4 is a side view of an agraffe embodying my invention.

Fig. 5 is a perspective view of said agraffe.

Fig. 6 is a side view of a different form of agraffe from that illustrated in Fig. 5.

Fig. 7 shows the manner in which the agraffe shown in Fig. 6 is retained in the piano frame.

In Fig. 1 wherein I have shown a portion of the frame of a grand piano, 1 indicates the frame which is formed with the usual capo tasto bar 2, and 3 indicates the piano strings.

In Fig. 2 wherein a portion of an upright piano is shown, 1 indicates the usual frame, 5 indicates the wrest plank in which the tuning pins 4 are received, 3 indicates the piano wires which are secured to the tuning pins, and 14 is the usual pressure bar which rests on the piano strings.

In some grand pianos the bar 2 has cast integral therewith a rib against which the piano strings 3 rest and which constitutes

an agraffe, the function of which is to determine the effective length of each string. Similarly, in some upright pianos the frame 1 has a similar rib cast thereon over which the strings 3 pass. In such pianos the correctness of the pitch and the quality of the tone of the note produced by any string depends to a considerable extent upon the agraffe, and it is, therefore, important that the rib should be of the proper height and at the proper location. Where this rib is cast integral with the piano frame, it is usual to finish it by filing it to the proper shape. This is a slow and laborious operation and, moreover, if the piano frame happens to have blow holes in the rib, then it is difficult to produce a properly-shaped rib.

One of the objects of my invention is to provide a novel agraffe of the type having a rib against which the piano wires rest, which agraffe is separable from the piano frame and is so constructed that the apex of the rib will always be properly positioned.

My improved agraffe comprises a body 80 portion 6 having a rib 7 formed on the outer face thereof against which rib the piano strings 3 rest. I propose to use a separate agraffe for each piano string or for the group of piano strings indicating any note. 85 Each agraffe will preferably be situated in a recess 10 formed in the piano frame, and the under face of the agraffe and the bottom of the recess have such a relation to each other that the agraffe will rest against the bottom of the recess only at the opposite edges 12. The purpose of this construction is to insure that the agraffe will have a firm seat on the recess bottom and will not be liable to rocking movement in the direction 95 of the piano strings. This seating of the agraffe against the recess at the opposite edges 12 only is herein accomplished by making the under face 8 of the agraffe concave, but the essential feature is to give the bottom of the recess and the bottom of the agraffe such relative shapes that the agraffe will have bearing at the opposite edges only. The agraffe may if desired be made with a stem 9 which occupies an aperture 11 formed 100 in the bottom of the recess, or the agraffe may be made without the stem 9, as shown in Fig. 6. The advantage of the stem 9 is that it assists in holding the agraffe properly in position.

It will be noted that the rib 7 over which the wires pass is situated between the two

bearing edges 12, and hence the pressure of the piano wire against the agraffe will hold it firmly in position.

In order to permit the agraffes to be set close together, each agraffe is preferably slabbed off at its sides, as shown at 13, thus reducing the width in a direction longitudinally of the rib 7.

The agraffe shown in Figs. 1, 2, 4 and 5 is constructed with the rib 7 integral with the body 6, and it is retained in place in the piano frame by the pressure of the piano strings thereagainst. I have shown in Figs. 6 and 7 a different embodiment of the invention wherein the body of the agraffe is made of some malleable metal and is constructed so that it can be forced into firm contact with the walls of the recess.

The under face 8 of the body 16 is concave so that when the agraffe is placed in the recess it will bear against the recess at the opposite edges 12 only. In using this form of agraffe, I propose to make the recess 10 of such a size that the agraffe will fit snugly therein and then after the agraffe has been placed in the recess, I propose to strike it a blow with a hammer or other implement which will operate to flatten the concave face and spread the edges 12 outwardly into firm contact with the walls of the recess, as shown in Fig. 7, the malleable nature of the body portion 16 permitting this operation.

It is desirable that the portion of the agraffe against which the piano strings rest should be hard instead of pliable and soft, and where the body of the agraffe is made of malleable metal, I propose to insert in the body a pin or bar 21 of hardened material, such as hard steel, and which forms a rest for the piano strings.

In the construction shown the body of the agraffe is provided with the raised portion 20 in which is formed a groove 17 adapted to receive the steel pin 21.

The pin 21 is retained in the groove 17 by making the groove of a depth slightly greater than the radius of the pin and then by pressing the upper edges of the groove 50 against the pin after the pin is inserted. This can be done by the same tool which is used to flatten the body and wedge it into the recess 10.

I claim:

1. In piano construction, the combination with a piano frame having a plurality of agraffe-receiving recesses, of an agraffe in each recess resting against the bottom there-

of and retained in position by the walls thereof, each agraffe having a concave under face, thereby forming at opposite sides two bearing edges which rest against the bottom of the recess.

2. In piano construction, the combination with a piano frame having a plurality of agraffe-receiving recesses, of an agraffe in each recess resting against the bottom thereof, each agraffe being prevented from lateral movement by the walls of the recess and having a transversely-extending rib on its outer face against which the piano string rests, and the under face of the agraffe and the bottom of the recess having such relative shapes that the agraffe engages the bottom of the recess only at two edges situated on opposite sides of the rib.

3. An agraffe comprising a body of malleable metal concaved on its under face and having a hardened string-supporting rib on its upper face, said body having a less dimension in a direction longitudinally of the rib than in a direction transverse thereto.

4. An agraffe comprising a body of malleable metal concaved on its under face and having on its upper face a rib of steel against which the piano strings rest, said agraffe having a less dimension in a direction longitudinally of the rib than in a direction transversely thereto.

5. In piano construction, the combination with a piano frame having a plurality of agraffe-receiving recesses, of an agraffe received in each recess, there being an agraffe for each piano string, each agraffe being formed of malleable metal and having a concaved under face thereby forming on opposite sides two bearing edges which rest against the bottom of the recess, the bearing edges of the agraffe being forced into firm engagement with the walls of the recess.

6. In piano construction, the combination with a piano frame having a plurality of agraffe-receiving recesses, one for each piano string, of an agraffe in each recess, each agraffe being formed of malleable metal and having a concaved under face thereby forming on opposite sides two bearing edges which rest against the bottom of the recess, the bearing edges of the agraffe being forced into firm engagement with the walls of the recess, said body having a groove in its upper face, and a hardened steel pin in said groove.

In testimony whereof, I have signed my name to this specification.

RICH'D. W. GERTZ.
